UNITED STATES PATENT OFFICE.

FRED F. MILLER, OF COMPTON, ILLINOIS.

RIVETING INSTRUMENT.

1,211,333.

Specification of Letters Patent.

Patented Jan. 2, 1917.

Application filed July 29, 1916. Serial No. 112,199.

To all whom it may concern:

Be it known that I, FRED F. MILLER, a citizen of the United States, residing at Compton, in the county of Lee and State of Illinois, have invented new and useful Improvements in Riveting Instruments, of which the following is a specification.

This invention relates to a device for facilitating the riveting of automobile or other pneumatic tires.

In carrying out my invention it is my purpose to construct a device of this character including a swinging member having one of its sides angular and formed with fingers which receive a head or disk of comparatively soft metal, such as lead, whereby to engage with the portion of the tire to be riveted to permit of openings being punched through the tire to receive the rivets, the opposite end of the swinging member having an upwardly extending portion terminating in a rounded or cone-shaped head or anvil which is of steel or other hardened metal whereby after the rivets have been passed through the openings and the washer arranged upon the ends of the said rivets, the said anvil will form a contact member against which the ends of the rivets are compressed and bent against the washer, when the said rivets are subjected to an impact of force, such as the blow from a hammer.

It is a further object of the invention to produce a device of this character that is so constructed and arranged as to be readily swung to a desired operative position.

With the above and other objects in view the improvement resides in the construction, combination and arrangement of parts set forth in the following specification and falling within the scope of the appended claims.

In the drawings: Figure 1 is a perspective view of a device constructed in accordance with the present invention, Fig. 2 is a sectional view approximately on the line 2—2 of Fig. 1, Fig. 3 is a sectional view approximately on the line 3—3 of Fig. 1, Fig. 4 is a detail sectional view approximately on the line 4—4 of Fig. 3, and Fig. 5 is a perspective view of the soft metal member employed.

While it is not essential in carrying out my invention in practice, preferably I employ a bench which is indicated by the numeral 1 and which may be of any desired construction. Upon the table 1 and projecting beyond one of the sides thereof

I secure a plate 2 and on the portion of the plate projecting a suitable distance beyond the side of the bench I provide a centrally arranged bearing opening 3 through which passes a bolt or other pivot member 4 that pivotally connects the base of the improvement to the said base 2. The pivot member 4 may have its lower end threaded whereby to receive a nut to sustain the pivot properly upon the said plate 2 and upon the improvement. The improvement contemplates the employment of a base 5 preferably comprising a substantially rectangular metal plate, the said plate having one of its ends 60 either integrally formed with or secured thereon an angular side member 6. The side member 6, adjacent to the upper edge thereof is provided upon its inner face with a pair of spaced angularly arranged members which 65 have their inner faces rounded or of an arcuate formation and providing the sides 6 with spaced fingers 7. These fingers are adapted to receive therebetween and to sustain the side plate 6 a disk of soft metal, such as lead 70 and which is indicated by the numeral 8. The disk includes an inner flat face which 75 rests against the upper portion of the side 6 and an outer rounded face which is engaged by the outer faces of the finger 7. 80

Upon the base 5, adjacent to the upper end thereof provided with the angular side 6 I preferably removably secure an upwardly extending or standard member 9 which has its upper end provided with a 85 rounded or cone-shaped head 10 providing the standard with what I will term an anvil and the said anvil is of some suitable hardened metal, such as steel.

The operation of the device may be 90 briefly described as follows: The bench provides for the reception of the tire and for the tools used in riveting the tire as well as the rivets. The device is swung upon its pivot to bring the angular side of the same 95 to a position convenient to the operator, preferably over the bench. The tire, at the portions thereof to be punched is brought over the lead disk 8, and suitable openings are made in the said tire by a punch which, 100 when subjected to an impact of force, such as the blow from a hammer will enter the disk but will not destroy the disk. When all of the openings are made by the punch rivets are passed through the alining openings in the overlapping portions of the tire 105 and washer members are placed upon the 110

ends of the rivets. The tire, during the process of inserting the rivets has been removed from the improvement and the swinging member is turned inward so that the angular 5 will be brought over the punch or to a convenient position with respect to the operator. The ends of the rivets are placed upon the anvil and the heads of the rivets are given a blow of the hammer, compressing the ends of the said rivets to widen the same and to force the same into engagement with the outer faces of the washers.

Having thus described the invention, what I claim is:

15 1. In a device for the purpose set forth, a pivoted member having an angular side, fingers upon the side, a disk adapted to be received between the fingers, and an anvil upon the member disposed opposite the said angular side.

20 2. In a device for the purpose set forth, a revolute member including a flat base, said base having an angular extension at one of the ends thereof, fingers formed upon the inner face of the said angular member, a disk adapted to be received between the said fingers, a standard upon the base adja-

cent to the end thereof opposite that provided with the angular member, and the upper end of the said standard being enlarged and of a substantially cone-shaped formation in plan, as and for the purpose set forth. 30

35 3. In a device for the purpose set forth, the combination with a bench having a plate extending beyond one of the sides thereof, a member including a base which is centrally pivotally connected to the extension of the base, said base having an angular side at one of the ends thereof, angularly disposed fingers upon the inner face of the side adjacent to the outer edge thereof, said fingers having their inner faces of an arcuate formation, whereby to receive the rounded face of a disk therebetween and 40 retain the inner flat face of the disk against the said side, a standard removably secured to the base and said standard having its outer end formed with a substantially cone-shaped anvil. 45

50 In testimony whereof I affix my signature.

FRED F. MILLER.
